UNITED STATES PATENT OFFICE.

BENJAMIN FRANK CASE, OF MITCHELL, INDIANA.

FIREARM.

1,040,881.

Specification of Letters Patent.

Patented Oct. 8, 1912.

Application filed May 14, 1912. Serial No. 697,299.

To all whom it may concern:

Be it known that I, BENJAMIN FRANKLIN CASE, a citizen of the United States, and a resident of Mitchell, in the county of Lawrence and State of Indiana, have invented a new and Improved Firearm, of which the following is a full, clear, and exact description.

My invention has for its object to provide one having an extractor movable longitudinally of the barrel, and rotatable therewith on a stud mounted on the breech piece, so that when the barrel is rotated the extractor will engage a member on the stud, which will hold the extractor against movement when the barrel is moved longitudinally away from the breech piece, the extractor in this way removing from the barrel the shell.

Additional objects of the invention will appear in the following complete specification, in which the preferred form of the invention is disclosed.

In the drawings similar characters of reference indicate corresponding parts in all the views, in which—

Figure 1 is a side elevation partially in section of a firearm embodying the invention, showing the firearm ready to be fired; Fig. 2 is a sectional plan view of the firearm, showing the extractor ejecting the shell; Fig. 3 is a sectional view on the line 3—3 of Fig. 1; Fig. 4 is a sectional view on the line 4—4 of Fig. 2; and Fig. 5 is a sectional view on the line 5—5 of Fig. 2.

By referring to the drawings it will be seen that the firearm has a breech piece 5, in which is secured a stud 6, the barrel 7 having a plate 8 with an opening 9, through which the stud 6 is disposed, this plate 8 also having grooves 10, which are connected with the opening 9, the key members 11, which are secured to the stud 6 being adapted to move in the said grooves 10 when the barrel is rotated on the stud to the position shown in Figs. 2 and 4 of the drawings, these key members 11 being normally engaged by the cam members 12, which are secured to the front face of the plate 8, as shown in Fig. 1 of the drawings. Secured to the barrel 7, and spaced from the plate 8, there is a flange 13, having an opening

in which the stud 6 is disposed, the barrel 7 being supported by this flange 13, and the plate 8 when it is rotated on the stud 6 to the position shown in Fig. 2. In the barrel 7 there is a groove 14, in which is disposed the ejector 15, the flange 16 of the extractor being normally disposed in a recess 17 in the barrel. This extractor 15 has an offset portion 18, with a recess 19, the forward terminal 20 of the extractor 15 being disposed in a guideway in the flange 13. The recess 19 is provided to receive the lug 21, on the stud 6, when the barrel with the extractor is rotated on the said stud so that when the lug 21 is disposed in the recess 19 the extractor 15 will be held against movement longitudinally of the stud, and when the barrel is moved forward, as shown in Fig. 2 of the drawings, the flange 16 of the extractor, which engages the rim 22 of the cartridge 23, will serve to extract the cartridge from the barrel.

In the lower portion of the plate 8 there is a recess 24, in which the bolt 25 on the finger loop 26 is normally disposed, this bolt 25, when it is disposed in the said recess 24, serving to hold the barrel in firing position. When the firearm has been fired, this bolt 25 is pulled rearwardly, which withdraws the bolt 25 from the recess 24 in the plate 8, when the barrel 7 is rotated to the right, as shown in Fig. 2 of the drawings. When the barrel has been so rotated, the cam members 12 are moved away from the key members 11, and the grooves 10 are moved in position to receive the key members 11, so that when the barrel 7 is moved forward, the key members 11 will travel in the grooves 10, to support the rear of the barrel against rotary movement when the cartridge 23 is extracted from the barrel by the flange 16 on the extractor 15, this extractor 15 being prevented from moving forward with the barrel 7 by means of the lug 21, which is disposed in the recess 19 in the extractor 15, as has been described.

A collar 29 is secured to the stud 6, against which the cam members 12 strike to limit the forward movement of the barrel relatively to the stud 6 and the breech piece 5. The spring 27, which is held against the flange 13 by the nut 28, serves

to move the flange 13 and with it the barrel 7 rearwardly, which will free the key members 11 from the grooves 10, and when the said key members have been freed from the 5 grooves 10, the rotation of the barrel 7 on the studs 6 will cause the cams to ride on the inner ends of the key members 11, to press the cams 12, and with the cams the plate 8, rearwardly, and against the breech 10 piece.

Having thus described my invention, I claim as new and desire to secure by Letters Patent:

1. A firearm having a breech piece, a 15 stud secured to the breech piece, a barrel having two members spaced apart with orifices in which the stud is disposed, there being extractor grooves in the members, an extractor disposed in the grooves, and having a set off portion with a recess, and a member on the stud for engaging the extractor at the recess, when the barrel is rotated on the stud for holding the extractor against movement with the barrel when the 20 barrel is moved longitudinally relatively to the stud.

2. A firearm having a breech piece, a stud secured to the breech piece, a barrel having a plate with an opening through 30 which the stud is disposed, there being a groove in the plate extending to the opening, resilient means for holding the barrel yieldingly toward the breech piece, a cam in the front face of the plate at one side of 35 the groove, a key on the stud for moving in the groove when the barrel is moved away from the breech piece, the cam engaging the key for holding the barrel toward the breech piece when the barrel is moved rearwardly 40 to a position with the plate free from the key, and the barrel is rotated.

3. A firearm having a breech piece, a stud secured to the breech piece, a barrel mounted to rotate on the stud, and to move 45 longitudinally relatively to the breech piece, an extractor for the barrel mounted to rotate therewith and to move longitudinally relatively to the barrel, and a lug on the stud with which the extractor is adapted to 50 engage, when the barrel is rotated for holding the extractor against movement when the barrel is moved away from the breech piece, resilient means for holding the barrel yieldingly toward the breech piece, and 55 means for locking the barrel to the breech piece in position for firing.

4. A firearm having a breech piece, a stud secured to the breech piece, a barrel having a plate at its breech with an opening 60 through which the stud is disposed, and a recess, a member spaced from the plate secured to the barrel and having an opening through which the stud is disposed, there being an extractor groove in the barrel, an

extractor in the groove, a member on the 65 stud with which the extractor engages when the barrel with the extractor is rotated on the stud for holding the extractor against longitudinal movement with the barrel, and a member on the breech piece having a bolt 70 normally disposed in the recess.

5. A firearm having a breech piece, a stud secured to the breech piece, a barrel having a plate with an opening through which the 75 stud is disposed, there being a groove in the plate extending to the opening, a cam on the front face of the plate at one side of the groove, and a key on the stud for moving in the groove when the barrel is moved away from the breech piece, the cam engaging the key for holding the barrel toward the breech piece when the barrel is moved rearwardly to a position with the plate free from the key and the barrel is rotated.

6. A firearm having a breech piece, a stud 85 secured to the breech piece, a barrel having a plate with an opening through which the stud is disposed, there being a groove in the plate extending to the opening, an extractor 90 for the barrel mounted to rotate therewith, 95 and to move longitudinally relatively to the barrel, means on the stud with which the extractor is adapted to engage when the barrel is rotated for holding the extractor against movement when the barrel is moved away from the breech piece, a cam on the front face of the plate at one side of the 100 groove, and a key on the stud for moving in the groove when the barrel is rotated and is moved away from the breech piece, the cam engaging the key for holding the barrel toward the breech piece when the barrel is moved rearwardly to a position with the plate free from the key and the barrel rotated to firing position.

7. In a firearm having a breech piece, a barrel mounted to move laterally and longitudinally relatively to the breech piece, an extractor for the barrel mounted to move laterally therewith and to move longitudinally relatively to the barrel, a lug with 110 which the extractor is adapted to engage when the barrel is moved laterally for holding the extractor against movement when the barrel is moved away from the breech piece, means for holding the lug in position relatively to the breech piece, resilient means for holding the barrel toward the breech piece, and means for locking the barrel to the breech piece in position for firing. 115

8. In a firearm having a breech piece, a barrel mounted to move laterally and longitudinally relatively to the breech piece, a member secured to the barrel and having a recess, there being an extractor groove in 120 the barrel, an extractor in the groove, a member with which the extractor is adapted to engage when the barrel with the extractor

is moved laterally relatively to the breech piece for holding the extractor against longitudinal movement with the barrel, means for holding the member in position relatively to the breech piece, and a member on the breech piece having a bolt normally disposed in the recess.

In testimony whereof I have signed my name to this specification in the presence of two subscribing witnesses.
